10 Claims

ABSTRACT OF THE DISCLOSURE

The post-obstetrical catamenial pad is in the form of an elongated body member which includes a relatively thick readily absorbent padded area with a narrower and thinner portion adjacent to the padded portion. This thin portion carries a medicament such as one particularly suitable for post-obstetrical disorders such as hemorrhoids. Additionally, a fluid impervious shield is under the medicament applying portion.

BACKGROUND OF THE INVENTION

Catamenial pads or sanitary napkins have long existed and are constantly undergoing improvement. Specialized pads have long existed for particular purposes. One such pad, for example, is described in U.S. Patent 654,856. The device therein is adapted for both catamenial purposes and for treating hernias by means of mechanical support. Additionally it is known to supply various catamenial pads with different substances which are designed to achieve deodorizing effects or to render the fluid colorless such as described in U.S. Patents 3,124,135 and 2,066,946. It is also known to provide sanitary napkins in general with fluid impervious sheets such as described in U.S. Patent 2,973,760. Other pertinent disclosures are found in U.S. Patents 144,145; 1,192,439; and 3,081,515.

Although those skilled in the art have been aware of such specialized catamenial devices from periods of time as far back as U.S. Patent 654,856, referred to above, there has never been a catamenial device or sanitary napkin which was specifically designed to satisfactorily treat problems or disorders attendant after birth. In view of the high birth rate there exists a definite need for such a device.

BRIEF SUMMARY OF THE INVENTION

An object of this invention is to provide a catamenial pad or sanitary napkin which is particularly suitable for post-obstetrical use.

A further object is to provide such a pad which is especially effective in treating hemorrhoids.

This invention takes into consideration the fact that during the post-obstetrical "period" the woman is not too active and thus does not require a catamenial pad of as large a contact area as in conventional pads. This invention also takes into account the fact that hemorrhoids is a problem frequently attendant after birth. Additionally, it is necessary to perform an episiotomy for most women giving birth to their first child. This invention takes into account above facts by providing a catamenial device having a padded area of smaller contact surface than with conventional devices whereby the remainder of the pad can function as a medicament applicator for supplying suitable medicaments for treating hemorrhoids or for healing incisions made during an episiotomy. For maximum comfort to the user the medicament applying portion is narrower and thinner than the padded portion which in turn may be thicker than conventional pads. Additionally a fluid impervious shield extends under the applying portion to confine the medicament on or near the surface in contact with the user.

2

The post-obstetrical catamenial pad may also include a number of advantageous features. For example the fluid impervious shield may extend to the padded area as well as the applying area to prevent leakage of the absorbed fluid. To further confine the absorbed fluid in the padded area the impervious shield may also extend as a wall between the padded portion and applying portion. The entire pad may be covered with a gauze overwrap and a plurality of oversize holes may be provided in a concentrated area of a padded portion to enhance its absorbing function. It is sufficient to have these oversize holes in a concentrated area since the fluid is discharged in a confined area. For added comfort the pad may be bowed both laterally and longitudinally so as to more closely conform to the user's body. Where the pad is designed for treating hemorrhoids the applying portion is made at least three inches long and is no greater than one and a half inches wide.

THE DRAWINGS

FIG. 1 is a side elevation view of a catamenial pad formed in accordance with this invention during use;

FIG. 2 is a plan view of a catamenial pad such as shown in FIG. 1;

FIGS. 3 and 4 are cross-sectional views taken through FIG. 2 along the lines 3—3 and 4—4 respectively; and

FIG. 5 is a perspective view of a portion of a modified pad in accordance with another aspect of this invention.

DETAILED DESCRIPTION

As best shown in FIG. 2, the catamenial pad 10 is in the form of an elongated body member having a pair of ends 12 which during use are secured to a suitable fastener 14 (FIG. 1) on the user. A portion 16 of pad 10 is made of a suitable readily absorbent material while an adjacent portion 18 is substantially narrower and thinner than the padded portion. The entire pad is encased in a gauze overwrap 20, the ends of which may constitute ends 12.

As shown in FIG. 3 a fluid impervious shield 22 extends under both padded portion 16 and narrower portion 18. Additionally shield 22 may be folded over as at 24 to form a wall or barrier between portions 16 and 18 as later described.

Since the user is generally not very active while using a post-obstetrical pad, the padded portion is made with less contact area than with conventional pads. Suitable dimensions, for example for padded portion 16 may be five inches long with the width being three inches and the thickness one and a quarter inch. The extra thickness provides for more absorptive ability of padded portion 16.

To further facilitate absorptive ability of padded portion 16 a plurality of oversize openings 26 are provided through the gauze overwrap into the padded portion. Since the absorbed fluid is discharged in a confined area it is merely necessary to arrange these oversize openings 26 in a concentrated portion of padded element 16. For example the oversize holes or openings are in an area of less than half the total surface of padded portion 16. The provisions of fluid impervious shield 22 and its folded portion 24 around padded portion 16 provides satisfactory barriers for preventing leakage of the absorbed fluid. In this respect it is noted that folded portion 24 is disposed adjacent the oversize openings 26. If desired the shield may be provided on all sides of padded portion 16, excluding the surface in contact with the user.

Portion 18 of pad 10 is advantageously utilized for medically treating common post-obstetrical disorders. For example when pad 10 is intended as a means of treating hemorrhoids, a suitable medicament is applied to portion 18. Such medicaments are for example Husk First-Aid

Ointment supplied by Bullock-Walker Manufacturing Company or 10% Benzocaine in KY Jelly supplied by Johnson & Johnson. These samples of course are merely illustrative and in no way intending to be limiting. Where portion 18 is designed for healing incisions from an episiotomy other suitable medicaments may be used such as for example ordinary petroleum jelly.

The provision of fluid impervious shield 22 under medicament applying portion 18 assures maintaining the medicament at or near the surface of applying portion 18 which is to be disposed against the body of the user.

Where pad 10 is intended to treat hemorrhoids the applying portion 18 is preferably from five to six inches long but must be at least three inches long so as to enable padded portion 16 to be disposed under the vagina and applying portion 18 to be disposed in the anal area.

To maximize the comfort of the wearer applying area 18 gently slopes from the relatively wide padded portion to a narrower applying portion. Applying portion 18 is preferably between one and one and a half inches wide but should not exceed one and a half inches in width or it may add unnecessary discomfort to the wearer. To further enhance the comfort of the wearer the catamenial pad is bowed both longitudinally and laterally as shown for example in FIGS. 3-4.

In accordance with another aspect of this invention which is shown in FIG. 5, the medicament is applied to a separate applying member which is provided over the gauze overwrap 20 so as to assure intimate contact between the medicament and the body of the user. To maintain the medicament free from contamination a removable cover sheet 28 is applied over applying member 26 and remains secured thereto until immediately before use.

Obviously many modifications and variations of the present invention are possible in light of the above teachings. It is therefore to be understood that within the scope of the appended claims the invention may be practiced otherwise than as specifically described.

What is claimed is:

1. A post-obstetrical catamenial pad comprising an elongated body member, the ends of said body member being adapted to facilitate the fastening of the pad on the user, a portion of said pad being relatively thick and made of a readily absorbent material, the remaining portion of said body member being adjacent to said padded portion and being thinner and narrower than said padded portion, a medicament being on said remaining portion whereby said remaining portion functions as a medicament applying portion, a fluid impervious shield being under said applying portion, said shield extending under both said applying portion and said padded portion, and said shield extending completely up the side of said padded portion adjacent to said applying portion.

2. A pad as set forth in claim 1 wherein said body member is bowed both longitudinally and laterally.

3. A pad as set forth in claim 1 wherein said medicament is of an anti-hemorrhoidal composition.

4. A pad as set forth in claim 1 wherein said applying portion is at least three inches long and is no greater than one and one-half inches wide.

5. A pad as set forth in claim 1 wherein a gauze over-

wrap covers said padded portion and said shield, an applicating member being over said overwrap on said applicating portion, said medicament being applied to said applicating member, and a removable cover sheet being over said applicating member.

5 6. A post-obstetrical catamenial pad comprising an elongated body member, the ends of said body member being adapted to facilitate the fastening of the pad on the user, a portion of said pad being relatively thick and made of a readily absorbent material, the remaining portion of said body member being adjacent to said padded portion and being thinner and narrower than said padded portion, a medicament being on said remaining portion whereby said remaining portion functions as a medicament applying portion, a fluid impervious shield being under said applying portion, said body member including a gauze overwrap around said padded portion and said applying portion, and a plurality of oversize holes being in the upper surface of said overwrap over a concentrated area of said padded portion.

10 7. A pad as set forth in claim 6 wherein said body member is bowed both longitudinally and laterally.

15 8. A pad as set forth in claim 6 wherein said medicament is of an anti-hemorrhoidal composition.

20 9. A pad as set forth in claim 6 wherein said applying portion is at least three inches long and is no greater than one and one-half inches wide.

25 10. A post-obstetrical catamenial pad comprising an elongated body member, the ends of said body member being adapted to facilitate the fastening of the pad on the user, a portion of said pad being relatively thick and made of a readily absorbent material, the remaining portion of said body member being adjacent to said padded portion and being thinner and narrower than said padded portion, a medicament being on said remaining portion whereby said remaining portion functions as a medicament applying portion, a fluid impervious shield being under said applying portion, said shield extending under both said applying portion and said padded portion and up the side of said padded portion adjacent to said applying portion, a gauze overwrap being around said body member and having a plurality of oversize holes in its top surface over a concentrated area of said padded portion, said body member being bowed both laterally and longitudinally, said medicament being of an anti-hemorrhoidal composition, and said applying portion being at least three inches long and no greater than one and one-half inches wide.
